UNITED STATES PATENT OFFICE.

FRANK R. PACKHAM, OF SPRINGFIELD, OHIO, ASSIGNOR TO THE AMERICAN
SEEDING MACHINE COMPANY, OF SPRINGFIELD, OHIO, A CORPORATION
OF OHIO.

SEED-DISTRIBUTER.

No. 857,195.

Specification of Letters Patent..

Patented June 18, 1907.

Application filed January 5, 1907. Serial No. 350,903.

To all whom it may concern:

Be it known that I, FRANK R. PACKHAM, a citizen of the United States, residing at Springfield, in the county of Clark and State 5 of Ohio, have invented certain new and useful Improvements in Seed-Distributers, of which the following is a specification.

My invention relates to means for distributing grain, such as wheat, oats, flax, beans, 10 etc. It is particularly adapted for use with grain drills of all ordinary types.

The object of the invention is to arrange the distributing devices so that they shall have capacity to sow a great variety of 15 seeds,—seeds that vary in size and character, such as wheat and oats regarded as medium size grains; small seeds, such as flax-seed; and Lima and kidney beans which are probably among the largest sown by grain 20 drill machinery. In this connection it should be remembered that very often ordinary grain, such as wheat, is subjected to treatment for special purposes which changes the character of the seed so that when I speak of 25 wheat and oats I speak of those seeds in normal condition. By my invention the grain drill is adapted to sow a great variety of seeds, and the arrangement is such that the operator of the machine can readily set the 30 mechanism by referring to a chart for any particular kind of seed.

In a general way, I have arranged one set of mechanism for adjusting the machinery for the character of seed to be sown, and I 35 have provided mechanism for adjusting the devices for different quantities of each particular kind of grain, and by furnishing a chart comprising a plurality of series of figures arranged in columns the operator can by referring to the chart determine how to adjust both for the character of the seed and for the 40 quantity to be sown. The arrangement is simple, since I employ only one set of figures for the adjustment of the character of grain 45 to be sown, and a single set of figures for the adjustment for the quantity to be sown, and there is little or nothing about the mechanism to confuse the operator.

It will be seen that my improvement relates 50 particularly to what are known as force feeds, and in these kinds of feeds the carrying element in forcing the seed through the distributer co-operates with its walls to put the seeds in the proper state of compres-

sion—a condition essential to effective work 55 by force feeds. This compression is necessarily a variable factor where changes in speed of the carrying element are to be made and with great variations in speed this compression of the seed becomes a very important element to consider.

It becomes apparent that while the distributor may be formed for one particular kind of grain which will be effective with all the desirable ring of changes in the speed of the 60 carrying element, it is an entirely different matter when this distributor is used for feeding a different kind of seed. I have discovered that the necessary compression in the feeding of this new kind of seed cannot be produced by relying upon changes in the speed 65 of the carrying element. It becomes necessary to reorganize the structure for the distinct varieties of seed already mentioned, so that the distributor will be adapted to each 70 particular variety in a manner that the changes of speed, made within fixed limits, will always cause the proper compression to insure the best results. These changes in speed are necessarily within fixed limits; for 75 the customary dimensions of the parts of the change of speed machinery will not permit an unlimited number of changes.

By utilizing two independent adjustments, one effecting a ring of changes in the speed of 80 the carrying element, and the other, while in no way affecting the speed of the carrying element, in effect rendering the co-operative element best adapted to produce through the varying force, exerted by the carrying element in all the usual changes in its speed, the necessary compression, I am enabled to produce a system which in combination with a chart is extremely simple and yet effective 85 for all kinds of sowing grain.

Referring to the drawings, Figure 1 is a perspective view of the distributing mechanism showing the hopper of the machine in part and the chart or key for the various adjustments located on the hopper immediately above the distributing mechanism. Fig. 2 is a side elevation of a set of distributing devices and the indicator for the adjustment for the various characters of seed. Figs. 3, 4, 5 and 6 are detail views of the 90 valve mechanism shown in four different positions. Fig. 7 is a detail view of the interior of one of the distributing devices. Fig. 8 is a 95 detail view of the interior of one of the distributing devices.

section on line $x-x$ of Fig. 2. Fig. 9 is a detail view of a distributor wheel and valve mechanism of another type commonly used. Fig. 10 is a rear view of this distributor. Figs. 11, 12, 13 and 14 are views of the valve showing four different positions of said valve. Fig. 15 is a side view of a distributor of the fluted feed type. Fig. 16 is a detail view of the parts of said distributor. Figs. 17, 18, 19 and 20 are detail views showing the adjustments in four different positions. Fig. 21 is a detail of the mechanism for adjusting for different quantities. Fig. 22 is a detail showing the indicator for the last-mentioned adjusting device.

Like letters of reference indicate like parts throughout the several views.

In the drawings, the driving shaft, which shaft is usually operated direct by the carrying wheels of the machine, (not shown) is indicated by a . This shaft is journaled loosely in bearings, a^1 , supported from the frame of the machine. The adjusting mechanism for providing for the varying quantities of the grain to be sown consists of a disk, a^2 , having its hub keyed to the shaft, a , so that the disk will rotate in unison with said shaft but is capable of longitudinal movement independent of the shaft. This is the ordinary change of speed disk commonly used in some types of grain drill, and the disk is held in normal position by a spring (not shown) which is located within the housing a^3 . A hand lever, a^4 , is arranged in the usual way for moving the disk longitudinally against the tension of the spring. I do not attempt to explain in detail these parts because the construction is familiar to anyone acquainted with grain drill mechanism.

The vertical shaft, a^5 , is supported by the sleeve, a^6 , (see Fig. 1) and this shaft supports a beveled pinion, a^8 , which is slidingly mounted on the shaft, a^5 , and a stirrup, a^9 , engages the hub of the beveled pinion in the usual way, so that when the change of speed disk, a^2 , is thrown out of normal position the beveled gear may be adjusted to different positions for the purpose of providing for the different quantities of grain to be sown. The stirrup, a^9 , is formed with figures which constitute an indicator, (Fig. 1) which indicate the different positions the beveled gear may assume on the vertical shaft, a^5 , corresponding with the number of concentric rows of teeth on the disk, which in this case are thirteen. A pinion, a^7 , is rigidly secured on the upper end of the vertical shaft, a^5 , and motion is transmitted from the disk, a^2 , through the beveled gear, a^8 , to said pinion, and this pinion is shown in mesh with the beveled gear, a^{10} , which is journaled securely on the feed shaft a^{11} . The feed shaft extends transversely across the machine and is supported loosely in bearings formed in the frame-work of the machine, and the arrange-

ment is such that motion is transmitted through the pinion, a^7 , and beveled gear, a^{10} , to said feed shaft. There is shown in series five distributors on this feed shaft, a^{11} , but it is very common to construct these machines with as many as twenty-two or twenty-four distributors, depending on the size of the machine.

Referring to Figs. 2 to 8 there is shown a distributing device of an ordinary type now in use comprising a wheel, b , of the internal flange type journaled on the feed shaft, a^{12} , and arranged to rotate in unison therewith. The wheel is surrounded by a casing and will act in the usual way as a force feed to carry the grain through the distributor. The grain is fed to the hopper, b^1 , (see Fig. 7) of the distributor, and from the hopper through the measuring channel, b^2 , until it reaches the discharge orifice shown in Figs. 3 to 6. In this particular type of internal flange distributor I have shown a valve, b^3 , fully described and explained in the patent issued to A. F. Mills, No. 813,054, dated February 20th, 1906. The link, b^4 , (Fig. 2) is pivotally connected to the rock arm, b^5 , which is rigidly secured to the shaft, a^{12} , and the indicator, b^6 , (Fig. 2) is secured to said shaft, a^{12} . A single series of figures b^7 , is shown in register with the indicator, and these figures are graduated as 1, 2, 3 and 4, thereby indicating four different positions that the valve may assume. This indicator b^6 , is adapted to spring into engagement with the notches on the dial in the usual way. The intermediate marks are for slight adjustments to provide for grain that varies in cleanliness. For instance, it is often desirable to make a slight adjustment for grain that is exceedingly dirty, but the numerals, 1, 2, 3 and 4 indicate normal adjustments for normal grains.

It is manifest that since the object of the lever and connecting mechanism just described is for the purpose of locating the cut-off valves, b^3 , and since the disk wheel with the various rows of teeth may be used solely for the purpose of obtaining quantity after the said valves, b^3 , have been located with reference to their adaptability to the different sizes of seed, that said lever and connections may be dispensed with and means provided on each seed distributor for individually or separately making the adjustment for adaptation to the grain or seed; it being understood that it is customary to make such adjustment but once and that prior to sowing the crop.

Referring to Figs. 9 to 14, I have shown a different form of valve than that already explained, but one commonly used. It is shown in combination with an internal flange distributor wheel and consists of a hook-shaped arm, b^8 , which is adapted to be oscillated on different positions in the measuring channel. The arm is pivoted upon the stud,

*b*⁹, extending from the casing of the distributor, and a rock arm, *b*¹⁰, projects from the rock shaft, *a*¹², (see Figs. 1 and 10) and has a slide formed at its free end which engages a 5 pin *b*¹¹, extending from the hook-shaped arm *b*⁸, and the parts are so arranged that when the rock shaft, *a*¹², is oscillated all the valves, *b*⁸, are operated by the connecting arms *b*¹⁰. Figs. 11, 12, 13 and 14 disclose four different 10 positions for this valve. In Fig. 12 it is shown in a position adjusted for seed of an exceedingly small character, such as flaxseed, while in Fig. 13 it is shown adjusted for ordinary grain, such as wheat; in Fig. 11 it is 15 shown adjusted for beans; in Fig. 14 it is shown adjusted for oats.

Referring to Figs. 15 to 20, there is shown the ordinary fluted feed distributing devices wherein the distributing wheel is indicated 20 by the reference letter *b*¹². The casing for the distributor (Fig. 15) is marked *b*¹³, and the formation of the casing is substantially as that shown in Fig. 7. Fig. 17 shows the mechanism adjusted for sowing exceedingly 25 small grain, such as flaxseed; Figs. 18, 19 and 20, for wheat, oats and beans. In this device, the distributing wheel is shifted by any ordinary mechanism, but by devices that are well known in the art it may be connected to 30 the rock shaft, *a*¹², in substantially the same manner as that shown in Fig. 1, so that whenever the rock shaft is moved the flange feed wheel will be shifted to proper position for the particular character of grain to be 35 sown. It matters not what particular type of variable throat distributing device is used or what type of valve mechanism is used therein, it will only be necessary to adjust the feeds in order to adjust for any particu- 40 lar kind of seed, which are indicated by cut-off dials conveniently arranged, and this adjusting mechanism in combination with the adjusting mechanism for the quantities of seed to be sown, and taken with the chart, 45 will provide a very wide range of adjustment for the seeding devices.

Referring now to the chart (Fig. 1) it is apparent that I have selected four types of grain which have distinct characteristics that 50 have to be provided for in any comprehensive distributing mechanism, and have appropriated spaces to each type. I have shown at the left end of the chart three series of figures which relate to sowing of flax. 55 The first column of figures indicates the different adjustments that the operator should make for the quantity, or, in other words, the adjustment of the change of speed device. Referring to this first column of figures, "1" indicates that the adjustment is such that the indicator plate, *a*⁹, is dropped until the figure 1 on that plate engages the pointer *x*. The next column indicates that if the operator adjusts the cut-off valve, *b*⁶, 60 to a position such that it will register with

the numeral 1 on the cut-off dial he will then be able to sow ten quarts of flax to the acre. Now referring to the last line in the column, if the operator adjusts the indicator rod, *a*⁹, to a point where the notch 6 will register with 70 the pointer *x*, leaving the cut-off dial indicating 1, he will then be able to sow twenty quarts of flax. Therefore it will be seen that I can first adapt the orifice to the size of the seed,—say flaxseed; the dimensions of the 75 discharge orifice being shown as especially adapted to a forceful discharge of this seed, and maintained for the usual ring of change for quantity, the efficiency of which is not lessened as in the old method where the 80 valve was changed each time a different quantity was desired. For it must be observed that it is a fact that but one sized opening produces the greatest efficiency in forcefulness, which in grain distributors 85 means an accurate amount for each revolution of the seed wheel. By this manner the quantity (except for slight variations for dirt and swollen grain) is obtained by means of the speed of the wheel or equivalent device. 90

Now referring to the series of figures showing the adjustments for wheat, it is apparent that by adjusting the cut-off dial to a different position, such as the figure 2, the operator can then ring up all the possible combinations of the change of speed device with that particular adjustment of the valve and he will be able to sow from sixteen quarts of wheat in progressive amounts as high as sixty-four. For oats, I have discovered that 100 by adjusting the cut-off dial to indicate "3" on the cut-off dial, my system will permit the machine to be adjusted for sowing from thirty-two quarts in progressive amounts as high as one hundred and twenty-eight to the 105 acre. For beans, by placing the indicator of the cut-off dial at the numeral 4, and making the ring of changes of the indicator rod, *a*⁹, the machine can sow from eighteen quarts to 110 sixty-seven.

Having thus described my invention, I claim:

1. A seed distributing mechanism for grain drills comprising a plurality of seed distributors, including a rotating carrying element for the seed, means for varying the size of the opening through which said seed is adapted to pass, driving mechanism for said distributors, and means for varying the speed of said distributors from said driving mechanism, an indicator for the distributor varying element and an indicator for the speed varying element, said indicators being each provided with a plurality of numbers, means tabulated with figures which represent variations in the respective indicators for both sets of adjusting mechanism, and co-operating to indicate the result for each combination, substantially as specified. 115

2. In a seed distributing mechanism for 120

grain drills, a plurality of distributors, each comprising a casing, distributing wheel and measuring channel, means for adjusting the size of said measuring channel, and means 5 for adjusting the speed of the distributing wheel, indicators for each of said adjusting means, each of said indicators being provided with a single series of figures co-operating therewith, and a chart comprising a 10 plurality of figures adapted to indicate the amount of seed sown by the mechanism for each combination of said adjusting mechanism, substantially as specified.

3. In a seed distributing mechanism, the 15 combination of a driving shaft, variable speed mechanism connected to said shaft, a series of distributors including distributing wheels, casings for said wheels having discharge orifices, means for varying the said 20 discharge orifices for different kinds of seed, and means for operating the variable speed devices for varying the quantity sown, indicators for each of said variable devices, one of said indicators indicating the character of 25 seed and the other indicating the quantity sown, and a table or chart to be read with said indicator comprising a plurality of figures for the different combinations of said indicators, substantially as specified.

30 4. In a seed distributing mechanism for grain drills, the combination of a plurality of seed distributing devices including a rotating carrying element for the seed, the variable mechanism for adjusting said seed distributors to different characters of seed, variable 35 speed mechanism for adjusting the speed of said carrying element to vary the quantity of seed carried thereby, indicators for each of said variable mechanisms indicating, respectively, the character of the seed sown and the quantity of seed sown, and a chart comprising a plurality of figures which represent variations in the position of the indicators for both adjusting mechanism and in-

dicates also the results of the combination 45 both as to the character of the seed and the quantity to be sown, substantially as specified.

5. In a seed distributing mechanism for grain drills, the combination of a plurality of 50 seed distributing devices including a rotating carrying element for the seed, a cut-off mechanism for adjusting for different characters of seed, and speed-adjusting mechanism for varying the quantities of seed fed by 55 the carrying element, an indicator for the first-mentioned mechanism, an indicator for the second-mentioned speed mechanism, each indicator being provided with a row of indicating points, and means co-operating 60 with the seed distributing mechanism for indicating the proper adjustments of the cut-off mechanism and the speed adjusting mechanism in accordance with the character 65 of the seed to be sown.

6. In a seed distributing mechanism for grain drills, a plurality of distributors, each comprising a casing, distributing wheel and measuring channel, means for adjusting the size of said measuring channel, and means 70 for adjusting the speed of the distributing wheel, indicators for each of said adjusting means, each of said indicators being provided with a single series of figures co-operating 75 therewith, and tabulated means having separate spaces for each character of grain, each space appropriated to one position of adjustment of said measuring channel and co-operating with said speed adjusting mechanism to indicate the varying 80 amount of grain sown, substantially as specified.

In testimony whereof, I have hereunto set my hand this 2nd day of January, 1907.

FRANK R. PACKHAM.
